UNITED STATES PATENT OFFICE

101,633

DESIGN FOR A GLASS BUILDING BLOCK

John R. Hoge, Toledo, Ohio, assignor to Owens-Illinois Glass Company, Toledo, Ohio, a corporation of Ohio

Application March 20, 1936, Serial No. 61,710

Term of patent 14 years

To all whom it may concern:

Be it known that I, John R. Hoge, a citizen of the United States and residing at Toledo, in the county of Lucas and State of Ohio, have invented a new, original, and ornamental Design for a Glass Building Block, of which the following is a specification, reference being had to the accompanying drawing, forming a part thereof.

In the drawing:

Fig. 1 is a fragmentary perspective view of a glass building block showing my new design.

Fig. 2 is a sectional view taken substantially along the line 2—2 of Fig. 1.

Fig. 3 is a fragmentary front elevational view illustrating the appearance of the block resulting from the provision of narrow diagonal ribs on the inner surface and relatively wide vertical ribs on the outer surface of the block.

I claim:

The ornamental design for a glass building block, substantially as shown and described.

JOHN R. HOGE.
